O. W. STOW, OF PLANTSVILLE, CONNECTICUT.

Letters Patent No. 72,561, dated December 24, 1867.

IMPROVEMENT IN MACHINE FOR FOLDING TINNED PLATES.

The Schedule referred to in these Letters Patent and making part of the same.

TO ALL WHOM IT MAY CONCERN:

Be it known that I, O. W. Stow, of Plantsville, in the county of Hartford, and State of Connecticut, have invented a new and improved Machine for Folding Tinned Plates; and I do hereby declare that the following is a full, clear, and exact description thereof, which will enable those skilled in the art to make and use the same, reference being had to the accompanying plate of drawings, forming part of this specification, in which—

Figure 1 is a front view of my invention.

Figure 2, an end or side view of the same.

Figure 3, a transverse vertical section of the same, taken in the line *z z*, fig. 1.

Figure 4, a plan or top view of the same.

Figure 5, a horizontal section of the same, taken in the line *y y*, fig. 1.

Figure 6, a transverse vertical section of the same, taken in the line *z z*, fig. 1.

Figure 7, a vertical longitudinal section of the same, taken in the line *z' z'*, fig. 5; and

Figure 8, a detached perspective view of a portion of the same.

Similar letters of reference indicate corresponding parts.

This invention relates to a new and improved machine for folding tin or tinned plates, for the manufacture of various articles of tin-ware; and it consists in the combination of a horizontal slide with the folding-bar, turning in adjustable bearings, with the cams and the bed-plate, so that the bar, in the progress of its revolutions, while turning a lock in the metal, can be made to rise or move in a direction to form a close or open lock or fold; and it further consists in the combination of the cams, folding-bar, and sliding pins, with the arms secured to the movable bed, fixed bearing, and horizontal slide, as will be hereinafter more fully described, whereby the sheet of metal shall be held securely in position during the operation of folding.

A represents a base-plate, having upright bars *B* attached, two near each end, and connected at their top ends by cross-plates *a*. These upright bars *B* serve as guides for bearings *C*, which are allowed to work freely up and down between them, and in these bearings the journals *b* of a folding-bar, *D*, are fitted and work. This folding-bar is constructed with two plane surfaces or sides *c c'*, which are at right angles with each other, as shown clearly in fig. 6, and on each journal, *b*, of the folding-bar, at the outer sides of the bearings *C*, there is secured a cam, *E*, shown in figs. 1, 2, and 4. *F* represents a bed, the same being attached to a bar, *G*, provided with a journal, *d*, at each end, fitted in fixed bearings *e*, on the base-plate *A*. This admits of a certain degree of vertical play of the bed *F*, the same being allowed to rise and fall to a certain extent, to admit of the tin *G* to be bent or folded, being inserted between the bed *F* and a fixed bearing-surface, *H*, as shown in fig. 6. The bed *F* has an arm, *I*, attached to it, at one or both ends, said arm or arms extending forward underneath the folding-bar *D*, near its ends, on which cams *J* are formed. One cam, *J*, and one arm, *I*, are only shown in the drawings. Through the rear upright bar *B*, adjoining the arm *I*, a horizontal sliding pin, *K*, is fitted, and allowed to work freely. This pin has a spiral spring, *f*, upon it, which has a tendency to keep the pin sufficiently far within the bar *B*, in which it is fitted, so that it will not interfere with the movement of the arm *I*; and the cam *E*, adjoining the pin *K*, has a groove, *g*, made in it, to allow the spring *f* to keep the pin *K* free from the arm *I*, (see fig. 3.) *L* is a slide placed longitudinally on the base-plate *A*, and provided at its rear side with two inclined surfaces, *h h*, shown more particularly in fig. 7, and the bearings *C C* extend down and catch or hook under these inclined surfaces, as shown in fig. 8, so that, by moving the slide *L* longitudinally, the bearings *C C*, and, consequently, the folding-bar *D*, admit of being raised under the action of the cams *E*, the latter bearing upon inclined surfaces *i i*, on the upper surfaces of the slide *L*.

The operation is as follows: In case it is desired to fold a piece of tinned plate with a close or tight fold, the slide *L* is adjusted to the left, as shown in figs. 1, 5, and 7, which causes the bearings *C* to be brought down to their fullest extent between the bars *B B*, and, by turning the folding-bar *D*, so that its plane surface or side *c* will be down in a horizontal plane, in front of the bed *F*, the sheet of tinned plate may be inserted between the bed *F* and the fixed bearing *H*, and over the surface or side *c* of the folding-bar, and, by turning the bar *D* over in the direction indicated by arrow 1, in fig. 6, the sheet of metal will be bent or folded with a close joint; but, by shoving the slide *L* to the right, so that the inclined surfaces *h* may be free from the lower hooked ends of the bearings *C*, the cams *E* will, as the bar *D* is turned, raise the bar *D*, and cause the metal plate to be

folded with an open joint, so that it may receive a wire. This open joint is shown formed in fig. 6. In turning the bar D to form the joint in the plate G $\times$, it is necessary, after the end of the plate has been inserted between the bed F and the bearing G, to have the front edge of the bed F press upon the plate G $\times$, to hold it firm; and this is effected by the cam or cams J, which act upon the arm or arms I, and force down the front end of the bed F. And, previous to said cam or cams leaving the arm or arms, the pin K is forced out by the cam E, adjoining it, over the arm I, underneath it, and the bed F is kept down by said pin, after the cam or cams have left the arm or arms.

Having thus described my invention, what I claim as new, and desire to secure by Letters Patent, is—

1. The slide L, in combination with the folding-bar D, cams E, bed F, and adjustable bearings C, operating as described, whereby the bar, in the progress of its revolution, may be raised or moved to form an open or close lock or fold, substantially as described, for the purpose specified.
2. The cams J E, pin K, and folding-bar D, in combination with the arms I, slide L, bed F, and fixed bearing H, all operating as described, whereby the metal plate G $\times$ is held securely in position while being folded, substantially as described, for the purpose specified.

O. W. STOW.
